4 Claims. (Cl. 103—234)

1

The present invention relates to apparatus for raising natural oils and other liquid by gaseous pressure by a displacement pumping system of the kind comprising a displacement chamber adapted to be located below liquid level in the well and an eduction pipe vertically reciprocating in said chamber and adapted to be moved into one position to isolate the chamber from the well and connect it with the eduction pipe to permit liquid collected in said chamber to be forced by gaseous pressure up the eduction pipe, the pipe being adapted to be moved into another position to shut off the supply of gaseous pressure, connect the interior of the chamber with the well to permit liquid to flow into the chamber and isolate the chamber from the eduction pipe.

In the known apparatus for raising oil by the displacement pumping system, as the oil enters a port at the lower end of the displacement chamber under the influence of gravity, it forces out any gas remaining in the chamber, the gas escaping through a port at the upper end of the chamber directly into the well casing. With this arrangement difficulties are experienced in pumping oil which contains volatile constituents as gas tends to separate from the liquid as soon as it enters the chamber. In these circumstances before the displacement chamber is filled completely, or to the desired level, a point is reached when the hydrostatic head of the column of separated oil partly filling the displacement chamber equals the hydrostatic head of the column of gassy oil outside, and consequently the entry of further oil into the chamber ceases before the chamber is filled.

It is an object of the present invention to provide means for preventing the aforesaid conditions and thereby ensure that the displacement chamber can be completely filled with oil irrespective of the degree of gassiness of the oil column in the well outside the chamber.

The present invention comprises apparatus for raising liquid in wells by the displacement pumping system, wherein liquid is collected in a displacement chamber from the well and subsequently raised up an eduction pipe by gas under pressure, an auxiliary chamber being provided with an exhaust port or ports for discharging the gas exhausted from the displacement chamber into the well casing at a distance above the chamber which is such that the hydrostatic head of a column of gassy oil in the well casing extending from the oil entry in the lower end of the displacement chamber to the height of the exhaust port or ports in the auxiliary chamber, is greater

2

than the hydrostatic head of settled or non-gassy oil which would fill the displacement chamber.

With this arrangement the gassy oil will flow into the displacement chamber until there is sufficient settled oil to fill the displacement chamber completely at each cycle of operation of the apparatus.

To enable this invention to be fully understood it will now be described with reference to the accompanying drawings, in which:

Figs. 1 and 2 are diagrammatic views illustrating the invention.

Fig. 3 is a schematic diagram illustrating the lay out of liquid raising apparatus embodying the invention.

Figs. 4 and 5 illustrate the working of the apparatus, and

Fig. 6 is a sectional elevation of the valve unit.

The operation of the pump is shown in Figs. 20 to 6 of the accompanying drawings wherein 1 is an oil well casing which is perforated to admit oil from the surrounding strata. The upper end of the casing is closed by a casing head 2 which supports a pipe 3 which extends through an aperture in the head 2 into the casing 1. A pipe 4 is provided adjacent the upper end of the casing for carrying off gas in the casing to a low pressure gas receiver 5.

The lower end of pipe 3 and the upper end of 30 a pipe 7 are connected by a collar 6 and the lower end of pipe 7 is provided with a collar 8 to which is connected a cylinder 9 and sleeve 10. The lower end of the sleeve 10 is connected with a collar 11 to which cylinders 12, 13 are attached.

The upper end of the casing 14a of the displacement chamber 14 is connected to the collar 11 and a sleeve 68, extending upwardly of the well rests on the packing ring 20 located on a shoulder on the outer face of the collar 11. The sleeve 40 68 engages the packing ring by gravity alone providing a simple seal against low differential pressures.

The collar 6 has a bore nearly equal to that of the cylinders 9, 12 and 13 and provides an inner shoulder forming a seat for the guide member 45 49 and forms a location point from which the positions of the parts connected with the pipe 3 can be related to the positions of the parts 46, 47, 48 constituting the reciprocating oil pipe.

The collar 8 has an internal recess 55 15 and apertures 16 connecting the interior of the cylinders 9, 12 with the annular space 17.

The collar 11 has vertical passages 18 connecting the space 17 with the chamber 14, and horizontal passages 19 connecting the interior of the

cylinders 12, 13 with the interior of the sleeve 68 without opening into the passages 18.

The lower end of the casing 14a is connected by a collar 21 with a cylinder 22 whose lower end is attached to a collar 23 which supports a casing 24 closed at its lower end by a plug 25. The chamber enclosed by the casing 24 forms a continuation of the chamber 14 and the combined dimensions of the two parts of this chamber, i. e., those enclosed by casings 14a and 24, are designed to allow the chamber to contain such a quantity of liquid, that when displaced into the oil education pipe, it will form therein a column of liquid of such length that the normal working gas pressure can force the column up the oil education pipe at the desired velocity.

A cylinder 30 extends between the collars 21 and 23, and the collar 21 is formed with slots 31 providing a passage between the interior of the casing 14a and the annular space 32.

The collar 23 is formed with vertical passages 33 connecting the annular space 32 with the interior of the casing 24 and horizontal passages 34 connecting the interiors of the cylinders 26 and 30 and an annular space between the cylinder 22 and a perforated screen 35 which extends between the collars 21 and 23.

A cylinder 26 depends from the collar 23 and its lower end is attached to collar 27 which supports an inner cylinder 28 and an outer sleeve 29 which terminates short of the plug 25. The collar 27 has a recess 36 and passages 37 connecting the interior of cylinders 26 and 28 with the annular space 38.

The cylinders 9, 12, 13, 26, 28 and 30 are all of substantially the same internal bore. The cylinders 9, 12, and 13 are concentrically arranged and comprise one group and the cylinders 26, 28, and 30 are concentrically arranged and form a second group.

The cylinders in the first mentioned group are nearly concentric with those of the second group. All the cylinders are machined internally to provide a high polish and are formed with flared or bell-mouthed upper and lower ends.

The upper end of the pipe 3 supports a cylinder 39 the upper face of which forms the base of a hydraulic cylinder 40 closed by a cap 41. A piston 42 is reciprocally mounted in the cylinder 40 and has integral hollow extension rods 43, 44 which extend through suitable packings in the upper and lower walls of the cylinder 40, the upper end of the rod 43 being adapted to engage a collar 45 on the oil education pipe 46 which extends through the rods 43, 44 and the piston 42 and interiorly of the pipe 3 down into the well.

The lower end of oil pipe 46 is connected by a pipe 47 with the upper end of an oil pipe 48 the pipe 47 being tapered to provide against any sudden change of velocity of the oil where the pipe has a larger internal diameter than the pipe 48.

The lower end of the pipe 47 and the upper end of the pipe 48 are connected by a slotted guide member 49 the outer diameter of which is an easy sliding fit in the pipe 3 and serves to guide and centralize the pipe 47 within the pipe 3. The guide is formed with vertical slots 50 to permit the free passage of gas.

The oil pipe 48 carries plungers 51, 52, 53, 54, 55, and 56 which operate within the cylinders 9, 12, 13, 30, 26, and 28, respectively. The lower end of the pipe 48 is closed and between the plungers 55 and 56 it is formed with a series of perforations 57. The various plungers form a

free sliding fit in the respective cylinders which are machined internally to reduce friction. The oil pipe 48 may be provided with spring guides (not shown) at points below the plungers 56 and 53, and also above the plunger 54 to centralize the pipe 48 and prevent damage to the plungers 51-56 as they are lowered into the respective cylinders. The upper end of the pipe 46 is connected by a flexible pipe 58 with an oil/gas separator 59.

A pipe 60 communicates with the cylinder 38 to deliver high pressure gas from a high pressure gas receiver 61. The piston 42 is actuated to raise the oil pipe 46 by fluid supplied under pressure from a container 62 connected to the lower end of the hydraulic cylinder 40. The fluid is forced from the container 62 by high pressure gas led by a branch pipe 63 from the pipe 60, the supply of gas being controlled by a valve 64 operated electrically by a timing device indicated by 65. The valve is of known two way type, adapted in one position to connect the interior of the container 62 with the pipe 63, and in the other position to connect the interior of the container to the exhaust connection 66. The container 62 is provided with a close-fitting piston 67 which serves to isolate the pressure fluid which may be oil, from surface contact with air or gas above the piston. When the container 62 is connected to exhaust the oil pipe 46 descends by gravity moving the piston 42 downwardly with it.

When the oil pipe 46 is in its lowermost position the piston 42 is at the lower end of cylinder 40, the slotted guide 49 is resting on the collar 6; the plunger 51 closes the upper end of cylinder 9; the plunger 52 closes the lower end of cylinder 12; the plunger 53 is below the end of cylinder 13; the plunger 54 closes the lower end of cylinder 30; and the plungers 55 and 56 are closing respectively the upper and lower ends of cylinder 28 isolating the perforations 57 of pipe 48.

With the apparatus in this position, oil from the casing 1 flows through the screen 35, passages 34, cylinder 26, recess 36 and passages 37, annular space 38 to fill the continuation or lower portion of the chamber 14. From thence the oil flows upwards within the casing 24 through passages 33, annular space 32, slots 31 and fills up the main portion of the chamber 14 formed by the casing 14a whilst gas that may be in the chamber is expelled through cylinder 13, passages 19, sleeve 68, and finally escapes to the casing 1 by holes 68a at the top of sleeve 68.

After a predetermined interval, the timing mechanism 65 actuates the pilot valve 64 and the piston 42 raises pipe 46 to the position shown in Fig. 3. In this position, plunger 55 is positioned in cylinder 26 whilst plungers 56 and 54 are raised higher up in cylinders 28 and 30 respectively. Plunger 51 is positioned in pipe 7 above the end of cylinder 9, plunger 53 is positioned in cylinder 13 closing its lower end whilst plunger 52 is raised in cylinder 12. Oil inlet passages 34 are then isolated between plungers 54 and 55 and the perforations 57 are in communication with the lowest portion of chamber 14 as formed by casing 24 via recess 36, passages 37 and annular space 38. Gas exhaust passages 19 are then isolated between plungers 52 and 53. Pressure gas is then permitted to flow from the gas container 61 via pipe 60, cylinder 39, pipe 3, cylinder 9, recess 15, passages 16, annular space 17, passages 18, to the top of the chamber 14.

Oil is then displaced by the gas pressure via slots

31, space 32, passages 33, down the outside and up the inside of sleeve 29, passages 37 and perforations 57 into the oil pipe 48, and thence through pipe 47 into pipe 46.

After the slug has travelled a suitable distance up the pipe 46, the valve 64 is actuated to exhaust the container 62 and the pipe 46 descends by gravity to the lowermost position cutting off further supply of gas pressure to the chamber 14. The expansion of the gas in the pipe 46 completes the delivery of the oil slug to the separator. The gas remaining in the chamber 14 is exhausted to the well casing via the exhaust sheath 68 and the chamber 14 refills with oil.

The particular point in the upward travel of the slug at which the pipe 46 is adapted to cut off the supply of pressure gas may be varied according to the slug velocity and the depth of the well.

The cut off will normally be effected to provide the use of gas in the pipe 46 expansively when the top of the slug has reached the surface. But in some cases the cut off may take place before, or after the top of the slug reaches the surface.

The cut off may be initiated by the cessation of electric current from the timing mechanism 65 to the electro-magnetic pilot valve 64 in which case the duration of pressure gas input is predetermined to suit well conditions.

The slug of oil flows from the pipe 46 through pipe 58 into the oil/gas separator 59 followed by the gas under pressure which is behind the slug.

The separator 59 has a float 69 provided with an arm 70 adapted to operate a projection 71 of a valve 72 which is connected by a branch pipe 73 with the pipe 60 and by a pipe 74 with a valve unit 75. As more particularly shown in Fig. 6, the valve unit comprises a main casing having an oil inlet 76 connected by pipe 77 with the lower end of the separator 59 and an oil outlet 78 having a spring-loaded valve 79 preferably embodying a dash-pot damping arrangement. The outlet 78 is connected by the pipe 79a, which includes an oil meter 80, with the oil receiver 81 from which it is delivered by the pipe 82 to a storage tank 83. The valve unit also includes a gas inlet 84, connected by a pipe 85 with the upper end of the separator 59, and a gas outlet 86 having a spring loaded valve 87, preferably embodying damping means. The outlet 86 is connected by the pipe 88 with a receiver 89 for gas at intermediate pressure. A further gas outlet 90 is provided which is connected by pipe 91 with the pipe 4 leading to the low pressure gas receiver 5.

The body of the valve unit has a valve seat 92 for engagement by a valve 93 provided with a spring 94 tending to open the valve. A screw plug 95 is provided for adjusting the pressure of the spring 94 to determine the pressure at which the valve opens.

A spindle 96 extends through the valve body and is provided with valves 97, 98 for co-operation with valve seats 99, 100 for controlling the flow of oil from the inlet 76 to the outlet 78. The spindle 96 also carries valves 101, 102 for co-operation with valve seats 103, 104 for controlling the flow of gas from the inlet 84 to the outlet 86. At the upper end the valve spindle is operated by a diaphragm 105 having a chamber 106 on the upper face, which is connected with the pipe 74.

The spindle 96 is provided with a spring 107

tending to raise the spindle and its lower end is formed with an extension 108 adapted to abut the valve 93 and maintain it closed when the spindle is in its lower position.

As the oil flows up the pipe 46 and into the separator 59, the valve spindle is in the position shown in Fig. 6, the oil valve 97, 98 being closed and the gas valves 93, 101 and 102 open so that the low pressure gas contained in the tubing 46 above the oil slug may be displaced at low pressure via the separator 59, pipe 85, valve 93, pipes 81 and 4 to the low pressure gas reservoir 5. The oil is adapted to enter the separator 59 tangentially to impart a spiral motion to the oil to assist separation of any gas therein, the gas under pressure which lifts the oil up the oil pipe, following the oil into the separator. As the level of oil rises in the separator, the float 69 is raised until the arm 70 depresses the projection 71 and actuates the valve 72 to permit pressure gas to flow to the chamber 106 via pipes 73 and 74 and move the spindle 96 to its lowermost position, opening the oil valves 97, 98 and closing the gas valves 93, 101 and 102. As soon as the necessary pressure has been built up in the separator 59 by the gas flowing into it, the oil is expelled through the pipe 77 and flows past the valves 97, 98, lifts the spring loaded valve 79 and flows through the pipe 79a and via the collector 81 and pipe 82 to the storage tank 83. When the oil in the separator has reached a predetermined low level, the arm 70 is lifted by the float 69 and the valve 72 returns by spring means to shut off the supply of gas from the pipe 73 and to connect the pipe 74 to atmosphere to exhaust the chamber 106.

The valve spindle 96 is now raised by its spring 107 to close the oil valves 97, 98 and open the gas valves 101 and 102, the valve 93 being free to open under spring action. The valve 87 is loaded by its spring to open at a predetermined pressure, for example 50 lbs. per square inch and the spring 94 is adapted to open the valve 93 below the predetermined pressure, which in the example given would be below 50 lbs. per square inch.

The gas in the separator flows through the pipe 85 to the inlet 84 and as it will normally be at a pressure in excess of that required to open the valve 87 this valve is raised by the gas which, however, maintains the valve 93 closed. The gas is delivered via pipe 88 to a receiver 89 for collecting gas at an intermediate pressure, which in the example is 50 lbs. per square inch. The gas is delivered from the receiver 89 via pipes 109, 110 to a gasoline extraction plant 111 and pipe 112 to the second stage intake B of a two stage compressor unit 113 which raises the pressure of the gas to the high pressure needed for operating the displacement pump and delivers it through pipe 114 to the high pressure receiver 61.

When the pressure of the gas flowing through the valve unit drops below the predetermined pressure of 50 lbs. per square inch, the valve 93 is opened by the spring 94 and valve 87 closes automatically. The remaining gas now flows past the valve 93 and through the pipes 91 and 4 to the low pressure gas receiver 5 and is delivered from there via pipe 115 to the first stage intake A of the two-stage compressor unit 113 wherein it is raised to the intermediate pressure and then delivered via pipe 110 plant 111 and pipe 112 to the second stage intake of the two-stage compressor 113.

On the next operation of the displacement pump a fresh slug of oil is delivered to the separator 59 and when the oil level therein rises suf-

75

ficiently, the valve 75 is actuated and the spindle 96 moved to its lower position and the cycle of operations described above is repeated.

Any surplus of low pressure gas, after making good any small losses in the closed system, is led through pipe 112a for use as fuel.

A reference to the diagrammatic views shown in Figs. 1 and 2 will enable the invention to be easily understood. As shown, Fig. 1 is a diagrammatic view of the prior arrangement of a displacement pumping chamber wherein *a* comprises the well casing, *b* the displacement chamber in which liquid is collected from the well through the aperture *c*. The eduction pipe is diagrammatically indicated at *g* and it will be understood that in actual practice this pipe is vertically reciprocated in the displacement chamber *b* and is provided with valve means which control the admission of the liquid through the ports *c* into the chamber *b* and the supply of fluid pressure to the chamber to displace the liquid from the chamber up the eduction pipe in accordance with the steps in the cycle of the displacement pump. For efficient operation it is necessary that the chamber *b* should be completely filled with liquid during each cycle of the pumping system. However, in pumping oil or liquid containing volatile constituents gas tends to separate from the liquid as soon as it enters the chamber *b*. In prior constructions this separated gas was adapted to be exhausted directly into the well through the ports *d* at the upper end of the chamber *b* as shown in Fig. 1. It was found that this arrangement did not ensure that the chamber *b* was completely filled with liquid due to the fact that when the hydrostatic head of the column *x* of settled or non-gassy liquid in the chamber *b* in Fig. 1, equalled the hydrostatic head of the column *y* of gassy liquid in the well casing, extending vertically from the inlet port *c* to the gas exhaust ports *d* the entry of further liquid into the chamber *b* ceased. Accordingly the volume of liquid collected in the chamber varied according to the percentage of volatile liquids in the liquid and the desired filling of the chamber to a constant level at every cycle of the pumping system could not be attained.

As shown diagrammatically in Fig. 2 this drawback is overcome by providing an auxiliary chamber *e* forming an upper extension of the displacement chamber *b*. The chamber *e* is formed with annularly arranged ports *f* exhausting gas into the well casing at a point spaced above the upper end of the chamber *b*. As liquid enters the chamber *b* it expels any separated gas into the chamber *e* through the annularly arranged ports *d'*. The chamber *e* is of such dimensions that the chamber *b* is completely filled with liquid before the point is reached wherein the hydrostatic head of the column of settled or non-gassy liquid *x'* in the displacement chamber equals the hydrostatic head of the column of gassy liquid *y'* in the well casing extending from the inlet port *c* in the chamber *b* to the gas exhaust ports *f*.

It will be understood that although the invention is particularly applicable to the apparatus described in my U. S. Patent No. 2,162,418 and my prior pending U. S. application No. 616,110 it may be adapted for use in other forms of displacement pumping apparatus.

I claim:

1. Apparatus for raising liquids in wells by gaseous pressure comprising a displacement chamber adapted to be disposed below liquid

level in a well, an auxiliary chamber extending from the upper end of said displacement chamber; gas inlet ports in the lower end of said auxiliary chamber opening into the upper end of said displacement chamber; gas outlet ports in said auxiliary chamber spaced upwardly of the upper end of the displacement chamber and opening into the well; a gas pipe opening to said displacement chamber; a source of gaseous pressure, means connecting said source to said gas pipe; an eduction pipe vertically reciprocable in said displacement chamber; a plurality of valve means actuatable by said eduction pipe upon reciprocation thereof to one position for admitting liquid to the displacement chamber from a space around the displacement chamber, uncovering the gas inlet ports connecting the upper part of the displacement chamber with the auxiliary chamber, and closing the eduction pipe from the displacement chamber; and actuatable, upon reciprocation of the eduction pipe to another position thereof, for closing said displacement chamber from said space, covering said gas inlet ports, admitting gaseous fluid to the upper part of said displacement chamber, and opening the eduction pipe to the lower part of the displacement chamber; said gas outlet ports in the auxiliary chamber being spaced such distance above the upper part of the displacement chamber that the hydrostatic head of a column of gassy oil in the well casing extending from the oil entry in the lower end of the displacement chamber to the height of the exhaust port or ports in the auxiliary chamber, is greater than the hydrostatic head of settled or non-gassy oil which would fill the displacement chamber.

2. Apparatus for raising liquids in wells by gaseous pressure comprising a displacement chamber adapted to be disposed below liquid level in a well; an auxiliary chamber extending from the upper end of said displacement chamber; a series of annularly arranged gas inlet ports in the lower end of said auxiliary chamber opening into the upper end of said displacement chamber; a series of annularly arranged gas outlet ports in said auxiliary chamber spaced upwardly of the upper end of the displacement chamber and opening into the well; a gas pipe opening to said displacement chamber; a source of gaseous pressure; means connecting said source to said gas pipe; and eduction pipe vertically reciprocable in said displacement chamber; a plurality of valve means actuatable by said eduction pipe upon reciprocation thereof to one position for admitting liquid to the displacement chamber from a space around the displacement chamber, uncovering the gas inlet ports connecting the upper part of the displacement chamber with the auxiliary chamber, and closing the eduction pipe from the displacement chamber; and actuatable upon reciprocation of the eduction pipe to another position thereof, for closing said displacement chamber from said space, covering said gas inlet ports, admitting gaseous fluid to the upper part of said displacement chamber, and opening the eduction pipe to the lower part of the displacement chamber; said gas outlet ports in the auxiliary chamber being spaced such distance above the upper part of the displacement chamber that the hydrostatic head of a column of gassy oil in the well casing extending from the oil entry in the lower end of the displacement chamber to the height of the exhaust port or ports in the auxiliary chamber, is greater than the hydrostatic head of

settled or non-gassy oil which would fill the displacement chamber.

3. Apparatus according to claim 1 wherein the said auxiliary chamber comprises a cylindrical member of substantially the same diameter as the displacement chamber.

4. Apparatus according to claim 1 wherein said gas outlet ports in the auxiliary chamber connect the interior of said chamber directly with the well space.
